This is a continuation-in-part of my copending application, Serial No. 184,152, filed September 11, 1950, for a stress breaker assembly for artificial dentures, which application is now pending.

UNITED STATES PATENT OFFICE

2,607,116

STRESS BREAKER ASSEMBLY FOR ARTIFICIAL DENTURES

Ralph J. Ludwig, Tucson, Ariz.

Application September 11, 1950, Serial No. 184,152

2 Claims. (Cl. 32—7)

1

This invention relates to artificial dentures and particularly the means for securing the same to the so-called abutment or anchor tooth next adjacent to the end of the denture, and the primary aim is to provide a unique, novel and strong assembly capable of securing the artificial denture in the operative position yet allowing for movement thereof without imparting destructive forces to the aforesaid abutment or anchor tooth. Another important object of this invention is the provision of unique and effective parts for embodying the broad concepts of the invention, which parts are so interrelated as to be capable of forming a coupling between the artificial denture and the anchor tooth as a sufficient amount of free movement is permitted to insure preservation of the anchor tooth, whether the artificial denture be of the removable or permanent type. A yet further aim of this invention is the provision of an assembly of the aforesaid character that is in the nature of a stress breaker disposed between an anchor tooth and an artificial denture to which a portion of the stress breaker is attached.

As is well known in the art, artificial dentures when secured to permanent teeth impart a tremendous amount of destructive strain to the said teeth and, within a relatively short period of time, destroy the anchor teeth and thereby cause the removal thereof and the remaking of the artificial denture to include the anchor tooth which has thus been rendered useless.

It has been found that the use of my stress breaker assembly for artificial dentures will absorb the normal movement of the said denture and thereby insure the permanent anchor tooth against actions that tend to destroy the same. Specific details of construction embodying minor yet important objects of the invention, the manner of creating the stress breaker and effectively utilizing the same will appear during the course of the following specification, referring to the accompanying drawing, wherein:

Fig. 1 is a perspective view of two bridges held in place and anchoring permanent teeth through the medium of the stress breaker embodying my invention.

Fig. 2 is a stretched-out, enlarged, detailed, perspective view of the parts forming that portion of the stress breaker that are anchored to the bridge or other artificial denture.

Fig. 3 is a sectional view through the parts shown in Fig. 2 after the same have been assembled together and with the clasp.

Fig. 4 is a similar view to Fig. 3 but with a part

of the head ground away to permit a relative movement between the post and sleeve; and,

Fig. 5 is an enlarged, fragmentary, detailed, sectional view taken on line V—V of Fig. 1.

In the illustrated embodiment of the invention, the removable bridge is broadly designated by the numeral 10 and comprises an acrylic base 12 and the restoration teeth 14. After the parts are constructed as shown in Figs. 2 and 3, anchor 16 is imbedded in base 12 in a manner hereinafter set down with post 18 extending through sleeve 20 and there held by head 22 which has been soldered to post 18 as at 24. A flange 26 on head 22 maintains the parts in the condition shown in Fig. 3 until the flange 26 and a portion of post 18 are ground away as illustrated in Fig. 4 and at a time to be hereinafter defined.

Sleeve 20 has a clasp 28 secured thereto, and this clasp embraces or grips the anchor tooth 30, as shown in Figs. 1 and 5. With the parts assembled as shown in Fig. 5, movement of the denture consisting of base 12 and teeth 14 through a path of travel in the direction of the arrow shown in Fig. 5 is permitted without imparting stress to anchor tooth 30.

Thus, the destructive action usually imparted to anchor teeth where there is no freedom of movement between the denture and anchor tooth is eliminated. Obviously, clasp 28 may be of a permanent character, and the bridge or artificial denture would not then be removable. This invention is not limited to either removable or fixed dentures, and the form of the parts may be different from that illustrated.

In many instances, after the insertion of any restoration in the mouth, there is an absorption of the process that allows the restoration to settle to a lower level, out of occlusion with the opposing teeth in the mouth. This is commonly known as "gum shrinkage." The stress breaker formed and installed as above described and illustrated eliminates entirely all of the stress which is usually placed on an abutment tooth or teeth and which is due to the aforesaid absorption of the process, for the stress breaker allows the restoration to move in its entirety downwardly over the gums and in an even manner without pivotal action about any fixed point, as has heretofore been the case where an artificial denture has been secured to an anchor tooth.

When the flange 26 is ground away as shown in Figs. 4 and 5, a uniform upward or downward movement of the restoration 10 and which includes all replacement teeth 14 will occur; and

post 18 together with the head 22 will ride vertically in a path parallel to the disposition of the axis of post 18.

In actual practice, the maximum movement is approximately three (3) millimeters, and the downward movement will be limited either by the shoulder 32 formed within sleeve 20 or by base 12 striking the upper surface of the underlying gum 34. In actual practice, it has been found that post 18 may be formed of fourteen (14) gauge round material with an approximate length of five (5) millimeters formed integrally with anchor 16 and extending upwardly from a shoulder 36 provided on said anchor 16. Post 18 must be perpendicular to the face of this shoulder 36.

Sleeve 20 is approximately four and one-half (4½) millimeters in length, and the lower portion or smaller bore of the sleeve between shoulder 32 and the normally lower or inner end of sleeve 20 slidably fits post 18. The bore of sleeve 20 between shoulder 32 and the normally upper end thereof slidably receives head 22 when flange 26 is ground away. After the said grinding, the thickness of head 22 is substantially one (1) millimeter; and, during the assembly, solder 24 is introduced within a V-shaped recess formed between post 18 and the bevelled surface 38 on head 22.

The technique and method of assembly is as follows:

First, wax the conventional case in the usual manner, then assemble the parts shown in Fig. 2, making certain that there is one (1) millimeter between anchor 16 and the upper part of the gum 34 to allow a thickness of acrylic forming a part of base 12 to lie between anchor 16 and the gum when the work is completed. Have the top of sleeve 20 flush with the top of the occlusal rest 40 in anchor tooth 30. To achieve this, grind off the top only of the post and sleeve 18 and 20 respectively until the required length is obtained.

Post 18 should then be bevelled at its upper end, and the head 22 attached to post 18 with sticky wax. The entire assembly should be micro-filmed and the wax in the clasp or abutment softened to receive the assembled parts upon application of pressure. Post 18 must be absolutely perpendicular, both lingually-buccally and mesially-distally. If an artificial denture having more than one stress breaker assembly is used, the posts thereof must be absolutely parallel to each other.

After the assembly is properly positioned, the wax should be extended up from a lingual bar retention to the small hole in anchor 16. The stress breaker assembly is then removed from the wax casting, after which casting takes place in the usual manner. After casting, clean the imprint in the clasp with fine stone. Also, clean that part of sleeve 20 to which will be soldered the clasp; join clasp 28 to sleeve 20 and attach anchor 16 to the lingual bar retention with sticky

wax. Invest in soldering investment, dry and then solder clasp 28 to sleeve 20; solder anchor 16 to lingual bar retention; and solder head 22 to post 18. Polish the casting in the usual way; assemble on model, set-up the teeth, and grind the tooth that contacts the sleeve 20 to a curvature that will fit the sleeve 20 as shown in Fig. 1. Process the case in the usual manner and finish the case completely.

After this is done, grind off the flange 26 as well as the top of post 18 and head 22 so that the upper face of post 18 and head 22 are flush with the top of sleeve 20 as shown in Fig. 5. The movement between sleeve 20 and clasp 28 should then be tested; and, if there is freedom to allow the sliding of post 18 within sleeve 20, the case is then ready for insertion into the mouth.

Having thus described my invention, what is claimed as new and desired to be secured by Letters Patent is:

1. A stress breaker assembly for an artificial denture including a base and restoration teeth, said assembly comprising an anchor tooth clasp having a bore formed therein; an anchor adapted to be embedded in the base of the artificial denture; a post on the anchor, reciprocably mounted in the bore; an internal shoulder formed in the bore; a head on the post movable toward and from the shoulder for limiting movement of the post in the bore in one direction; and a shoulder on the clasp engageable with the anchor for limiting movement of the post in the opposite direction.

2. A stress breaker assembly for an artificial denture of the type adapted to rest upon the gum of the wearer and including a base and restoration teeth, said assembly comprising an anchor-tooth clasp having a bore formed therein and disposed with the axis thereof perpendicular to the top of the gum upon which the denture is to rest; an anchor adapted to be embedded in the base of the artificial denture; an elongated post on the anchor and reciprocably mounted in the bore for movement therein permitting movement of the denture toward the underlying gum, whereby to allow the denture to rest upon the gum as the latter shrinks after application of the denture, said post and bore being formed to prevent lateral movement of the denture radially of the post and swinging movement of the anchor relative to the clasp transversely of the longitudinal axis of said post.
